UNITED STATES PATENT OFFICE.

FRANK H. NORRIS, OF ROBINSON, ILLINOIS, ASSIGNOR OF ONE-HALF TO DANIEL E. NORRIS, OF ROBINSON, ILLINOIS.

SUCKER-ROD ELEVATOR.

1,275,728.

Specification of Letters Patent. Patented Aug. 13, 1918.

Application filed February 11, 1918. Serial No. 216,496.

To all whom it may concern:

Be it known that I, FRANK H. NORRIS, a citizen of the United States, residing at Robinson, in the county of Crawford and State 5 of Illinois, have invented new and useful Improvements in Sucker-Rod Elevators and the Method of Making the Same, of which the following is a specification.

This invention relates to sucker rod elevators and the method of making the same 10 and consists in certain improvements therein as will be hereinafter fully described and pointed out in the claim.

Sucker rod elevators have required a very 15 distinct shape in the art and consist of a body from which extend supporting arms within which is swiveled a supporting wrench plate. A center finger is secured to the body and extends into position to lock 20 the sucker rod in the wrench plate when the body is in an upright position. Heretofore the elevator body has been formed by shaping the arms on extensions which are united by welding. The centering finger has been 25 secured to the body thus formed by a short weld, this weld requiring a second heat. The elevator body so made is often defective especially with relation to the weld of the center finger and also requires additional 30 time incident to the second heat in making the weld. The object of my invention is to improve the elevator as to the manner of securing the centering finger and also improve the method of manufacture.

35 The invention is illustrated in the accompanying drawings as follows:—

Figure 1 shows the assembled elevator.

Fig. 2 one of the arms with its extension before the body is assembled and shaped.

40 Fig. 3 the centering finger before assembled in the body.

Fig. 4 the opposite arm to that shown in Fig. 2, with its extension prior to being assembled in the body of the elevator.

45 1 marks the supporting wrench plate and 2 the wrench socket therein. This socket is, as is well understood, designed to engage the end of a sucker rod joint so as to facilitate in the connecting and disconnecting of such

joint and also to be used in supporting the 50 rods as they are elevated or placed in the well. The supporting plate has the trunnions 3 which are swiveled in the arms 4. The arms 4 extend from a body 5. A center finger 6 also extends from the body 5 into 55 position to close the socket 2 when the body is brought to an upright position, the purpose being to lock the joint in place in the usual manner.

The body 5 has the swivel pin 7 formed 60 on its upper end which extends through an opening 8 in the ring 9. A shoulder 10 is arranged on the body below the pin 7 and the pin is headed over at 11 so as to lock the ring in place on the pin. 65

In forming the elevator the arms 4 are formed with the extensions 12 and 13 as shown in Figs. 2 and 4 and the finger 6 is formed with an extension 14 as shown in Fig. 3. These extensions are preferably of 70 equal length and are heated to a welding heat, brought together and welded, the head 10 and pin 7 being formed with the same welding heat, in fact, the fashioning of the swivel end of the body assists in forming the 75 weld. Further it will be observed that a portion of each extension is carried through into the head 11. This assists in holding the parts as well as the weld. By this construction the danger of a separation of the finger 80 from the shank, or body, formed by the extensions is entirely removed and at the same time the body can be more quickly manufactured.

What I claim as new is:—

In a sucker rod elevator, the combination of a swiveled supporting wrench plate; a body having arms in which said plate is swiveled; a retaining finger; a shank formed by united integral extensions of said arms 90 and finger; and a supporting ring swiveled on the shank, the extensions from the arms and finger extending into and forming an engaging part of the swivel.

In testimony whereof I have hereunto set 95 my hand.

F. H. NORRIS.
